UNITED STATES PATENT OFFICE.

WILLIAM F. HOLSING, OF UNIONTOWN, PENNSYLVANIA.

EXHAUST-STEAM CONDENSER FOR STEAM-PUMPS.

SPECIFICATION forming part of Letters Patent No. 268,100, dated November 28, 1882.

Application filed September 29, 1882. (No model.)

To all whom it may concern:

Be it known that I, WILLIAM F. HOLSING, a citizen of the United States, residing at Uniontown, in the county of Fayette and State of Pennsylvania, have invented a new and useful 5 Exhaust-Steam Condenser for Steam-Pumps, of which the following is a specification, reference being had to the accompanying drawings.

Figure 1 is a vertical sectional view, and 10 Fig. 2 is a transverse sectional view on the line *x x*, Fig. 1.

Similar letters of reference indicate corresponding parts in both figures.

This invention relates to exhaust-steam condensers for steam-pumps.

In mines and other places where it is frequently necessary to keep large steam-pumps constantly at work night and day much difficulty has been heretofore experienced in effectually disposing of the exhaust-steam, which 20 frequently accumulates in such quantities as to make it almost impossible to approach the pump. Attempts have been made to utilize the exhaust-steam for heating the feed-water; 25 but it has never to my knowledge been successfully disposed of in this manner.

My present invention therefore has for its object the construction of a device whereby the exhaust-steam shall be effectively condensed 30 and disposed of, and this great nuisance in mines done away with.

In the drawings hereto annexed, A represents the suction-pipe leading to the steam-pump, which is not shown in the drawings. 35 Said pipe is provided with an enlarged section forming a casing, B, within which is arranged

a cylindrical drum or chamber, C, secured or connected to the walls of the casing B by brackets D, or in any suitable manner. The lower end of drum C is closed. Its upper end has a 40 cover, E, provided with small perforations F. G is the exhaust-steam pipe, which extends through the shell of casing B, as shown, just above the drum or chamber C. Here it is provided with an elbow, H, in which is fitted a 45 pipe, I, extending through the cover E into and nearly to the bottom of the chamber C.

The operation of my invention will be readily understood. The exhaust-steam, passing through the pipes G I, enters the chamber C, 50 which is completely surrounded by the cold water passing through the suction-pipe to the pump. Here it is readily condensed, the water of condensation passing through the perforations F into casing B, and through pipe A 55 to the pump.

I claim and desire to secure by Letters Patent of the United States—

The combination of the suction-pipe A, having enlarged section or casing B, the chamber C, arranged within said casing, and having closed bottom and perforated top, and the exhaust-steam pipe G I, passing through the casing B and cover E into and nearly to the bottom of the chamber C, as set forth.

In testimony that I claim the foregoing as my own I have hereto affixed my signature in presence of two witnesses.

WM. F. HOLSING.
